BOTTLE SEAL FOR BOTTLE FILLING MACHINES

George L. N. Meyer, Milwaukee, Wis.

Application July 23, 1947, Serial No. 762,931

5 Claims. (Cl. 226—115)

1

This invention relates to bottle filling machines, and more particularly to a bottle seal to be used in connection with bottle filler valves.

In bottle filling machines heretofore devised, the filler valve was a separate unit which was inserted in the filler bowl individually. The bottle seal which is interposed between the filler valve and the bottle was an integral part of the valve element, and hence to change the bottle seal when that unit became worn out, necessitated emptying the filler bowl and withdrawing the filler valve. The valve could then be disassembled and the bottle seal replaced. This operation required considerable time and necessitated the complete stoppage of filling during the change-over period.

It is an object of the present invention to provide a filler valve having a seal which may be replaced without disassembling the valve.

Another object is to provide a bottle seal which will cushion the entrance of the bottle into the valve.

A further object is to provide a bottle seal which will reduce the time required to change the seal.

A still further object is to provide a filler valve in which bottle seals may be changed without draining the filler bowl.

A still further object is to reduce the breakage of bottles in bottle filling machines.

A still further object is to provide a filler valve having an improved bottle seal.

Other objects will become apparent upon consideration of the following specification, which, when taken in conjunction with the accompanying drawings, illustrate a preferred form of the invention.

In the drawings:

Figure 1 is a transverse cross section through a filler bowl, showing the improved filler valve in place therein;

Figure 2 is an elevational view of the bottle seal and retainer ring; and

Figure 3 is a disassembled view of the three parts constituting the bottle seal assembly.

Referring to the drawings, the filler valve comprises a cage 10 having openings 11 therethrough to permit the entry of liquid, the cage extending from a seat 12 in the base of the bowl 13 to an elevation above the high liquid level in the bowl. The lower end of the cage contains a liquid valve 15 having a hollow stem 16 for the passage of gas, the stem 16 extending above the maximum level of the liquid in the bowl.

The upper end of the stem 16 is guided by a

2

block 17, which is attached to the stem 16 and fits in a bearing in the upper end of the cage 10. A spring 19 urges the block 17 and the valve 15 into uppermost position, with the valve 15 open to permit the flow of liquids around the valve and downwardly along the exterior of a tube 20 into a bottle 21. Flow of gas through the tubes 16 and 20 into the bottle 21 is controlled by a valve 23 covering the upper end of the tube 16. A spring 25 urges the valve 23 into open position. The valve 23 is actuated by a cam 26, while the valve 15 is moved to open position by gas pressure beneath the valve 15. Both the valves 15 and 23 are closed by movement of the cam 26.

A wire screen 27 is mounted in a valve seat 28, below the liquid valve 15, and prevents the flow of liquid downwardly into the bottle when the pressure within the bottle equals the pressure in the bowl.

For further details of the operation of the valves 15 and 23 see U. S. Patent #2,063,326 to George L. N. Meyer, dated December 8, 1936, entitled "Filler Valve."

A bottle seal retainer ring 30 is mounted on the lower end of the filler valve. The retainer ring 30 includes an annular shoulder 32 engageable by a U-shaped fork 33 which holds the entire filler valve assembly in place through a bolt 35. The retainer ring 30 has a centrally located aperture 31 extending axially through the ring, which receives a rubber sealing ring 40 having the same outside diameter as the inside diameter 37 of the retainer. The sealing ring 40 contains an axial aperture 42 which receives a washer 44 which extends above the top of the ring 40 and seats in a corresponding aperture in the lower surface of the valve seat 28 to center the sealing ring assembly with the remainder of the filler valve. The lower portion of the sealing ring 40 has an enlarged aperture 46 of sufficient diameter to accommodate the neck of the bottle 21 entering the filler valve, and has a skirt 47 having a frustro-conical surface 48 to guide the bottle into the filler valve.

Since the outside diameter of the sealing ring 40 is equal to the inside diameter of the sealing ring retainer 30 the ring 40 is retained within the sealing ring retainer 30 by friction and forms an effective seal against the escape of liquid and gas. To replace the seal 40 it is merely necessary to pull downwardly on the skirt 47 and replace the seal 40 by inserting a new one in lieu thereof without the necessity of emptying the filler bowl.

It will be realized that the hereinbefore described form of the invention is to be taken merely as the preferred embodiment thereof, and that various changes in size, shape and arrangement of parts may be made without departing from the spirit of the invention or the scope of the subjoined claims.

That which is claimed as new and is desired to be secured by United States Letters Patent is:

1. In a bottle filling machine of the character described, a filler bowl, a filler valve in said bowl, a retaining ring in engagement with said filler valve, means to secure said ring against said filler valve to retain the valve in the bowl, a bottle seal mounted within said ring in frictional engagement therewith and having an aperture therein for the passage of liquid therethrough, a skirt on said bottle seal extending below the lower edge of the retainer ring to form a guide for bottles entering said valve.

2. In a bottle filling machine of the character described, a filler bowl, a filler valve in said bowl, a retaining ring in engagement with said filler valve, means to secure said ring against said filler valve to retain the valve in the bowl, a bottle seal mounted in said ring and having an outside diameter equal to the inside diameter of the ring whereby the seal is retained in the ring by friction only, an aperture through said bottle seal to permit the passage of liquid therethrough, and a skirt on the lower end of said bottle seal extending over said retaining ring to form a guide for bottles entering the filler valve.

3. In a bottle filling machine of the character described, a filler bowl, a filler valve in said bowl, a retaining ring in engagement with said filler valve, means to secure said ring against said filler valve to retain the valve in the bowl, a sealing element having a friction fit within said ring, said sealing element having an opening to receive a vent tube and to provide a passage way for liquid between the vent tube and the

element, and a bottle sealing surface on the lower side of the sealing element.

4. In a bottle filling machine of the character described, a filler bowl, a filler valve in said bowl, a retaining ring in engagement with said filler valve, means to secure said ring against said filler valve to retain the valve in the bowl, a sealing element having a friction fit within said ring, said sealing element having an opening to receive a vent tube and to provide a passage way for liquid between the vent tube and the element, a bottle sealing surface on the lower side of the sealing element, and a skirt formed on the lower side of the sealing element to form a guide for bottles entering the filler valve.

5. In a bottle filling machine of the character described, a filler bowl, a filler valve in said bowl, a retaining ring in engagement with said filler valve, means to secure said ring against said filler valve to retain the valve in the bowl, a sealing element having a friction fit within said ring, said sealing element having an opening to receive a vent tube and to provide a passage way for liquid between the vent tube and the element, a metal tube carried in and extending through said opening, and a bottle sealing surface on the lower edge of said element at the lower edge of the said tube.
